DESIGN FOR A CLOTHESPIN

Florindo F. Renzi, Leominster, Mass., assignor to
A. J. Renzi Plastic Co., Leominster, Mass., a
partnership consisting of Florindo F. Renzi and
Anthony J. Renzi

Application November 27, 1946, Serial No. 135,127

Term of patent 14 years

(Cl. D17—6)

To all whom it may concern:

Be it known that I, Florindo F. Renzi, a citizen of the United States, residing at Leominster, in the county of Worcester and State of Massachusetts, have invented a new, original, and ornamental Design for Clothespins, of which the following is a specification, reference being had to the accompanying drawing, forming a part thereof.

Figure 1 is a front elevational view of a clothespin showing my new design.

Figure 2 is a side elevational view of the clothespin shown in Figure 1; and

Figure 3 is a top view showing in plan the head of the clothespin shown in Figures 1 and 2.

I claim:
The ornamental design for a clothespin, as shown.

FLORINDO F. RENZI.
